UNITED STATES PATENT OFFICE

JOSEPH R. THOMAS, OF FORT MADISON, IOWA, ASSIGNOR OF ONE-HALF TO THE ROME COMPANY, INC., A CORPORATION OF NEW YORK

CONVERTIBLE FURNITURE

Application filed August 3, 1927. Serial No. 210,415.

This invention relates to improvements in convertible furniture and especially to a combined chair or settee and bed, having for an object to provide an article of furniture 5 constructed in a manner that when in its normal position, the same will simulate a chair or settee of the overstuffed upholstered type, affording those elements or qualities of comfort and ease common to such furniture, 10 while by simple and convenient manipulation, the article may be converted into a bed possessing equally comfortable qualities.

It is also an object of the invention to provide a convertible article of furniture including bed frame sections so constructed and mounted upon the body portion that the same may be extended to operative position by applying an outward pull thereto, causing said sections to be automatically moved 20 from their inoperative and substantially superposed relation to juxtaposed relation, in which latter position, they are firmly supported whereby to provide an efficient spring bed, the sections, when no longer desired for use 25 as a bed, being easily returnable to their folded or inoperative positions whereupon the article may be used as a chair or a settee.

The invention furthermore includes amongst its principal desiderata, the provision of a bed including sections for constituting the same, such sections having a novel arrangement of mounting levers and connecting links operative with the imparting 30 of an outward pull to one of the sections to effect their extension in tandem or juxtaposed relation, imparting to the respective sections that compound movement necessary to bring about an operative extension of the same.

Other objects of the invention will be in part obvious and in part pointed out hereinafter.

In order that the invention and its mode of 45 operation may be readily understood by those skilled in the art, I have in the accompanying illustrative drawings and in the detailed following description based thereupon, set out one possible embodiment of my invention.

In these drawings:

Figure 1 is a vertical transverse section through the improved article of furniture.

Figure 2 is a similar section showing certain of the bed forming sections in open position at the first stage of their operation to extended or bed constituted positions, 55

Figure 3 is a fragmentary vertical transverse section through the article of furniture showing the second step or stage of operation 60 of the bed constituting positions in their extended or operative positions,

Figure 4 is a similar view showing the final stage of operation of the bed constituting sections and wherein said sections are in 65 their extended positions, and constituting a bed,

Figure 5 is an enlarged vertical fragmentary section through certain of the mattress sections of the bed forming portion of 70 the invention showing the manner in which these sections are normally retained in nested or superposed relation, as when the bed is in its folded or inoperative position,

Figure 6 is a fragmentary vertical transverse section through a slightly modified form of the construction in which but two bed frame constituting sections are utilized and 75

Figure 7 is a similar view showing the bed 80 constituting sections of the modified form of the invention in their extended or operative positions.

Having more particular reference to the drawings, in connection with which like characters of reference will designate corresponding parts throughout, the article of furniture may be stated to comprise a body portion either in form of a chair or settee, preferably of the overstuffed upholstered type, such as 85 generally indicated herein by the numeral 1, the sides and the back, 2 and 3 respectively of the article being suitably upholstered as is indicated; the back portion of the article having a rearwardly disposed chamber 90 formed throughout its length and designated by the numeral 4, the purpose of which will be subsequently described. The outer side of this chamber 4, as will be noted, is closed by a suitable wall of partitioning material 5, 95

while feet 6 may also be provided the article, their arrangement being varied to accord with the particular requirements.

Normally received within the lower portion of the article 1 are a plurality of bed frame constituting sections numbered 7, 8 and 9, each of said sections including suitable metal frames, receiving and supporting therein engaged and relatively interconnect- 10 ed coiled springs 10, or other effectual spring arrangements or constructions well known in the art at this time.

The section 7 is connected to its adjacent section 8 through the medium of links 11 fixedly connected to the inner extremities of the opposite sides thereof through the medium of rivets 12, while the outer or extended and free ends of these links are pivoted as at 13 to suitable ear like bearing extensions arranged upon the adjacent end portions of the opposite sides of said section frame 8. That portion of the frame section 8 outwardly of the pivotal connections 13 is provided upon its opposite sides with bearing ears 14 to which links 15 are pivotally connected, the remaining extremities of said links being pivoted to offset fingers 16 fixedly mounted upon the adjacent extremities of the opposite sides of the frame section 9. It 30 will be thus seen that pivotal interconnection is effected between the bed frame constituting sections 7, 8 and 9; the free and normally outer portion of said frame section 9 carrying a panel or cover board 17 thereon, the width of which is equal to the combined depth of the spring carrying sections 7 and 9 when in those positions as is shown in the Figure 1, whereby to afford a finishing and protective outer covering for the same.

40 Motion transmitting and frame adjusting levers are arranged adjacent the opposite side portions of the frame sections 7, 8 and 9 inwardly of the opposite sides 2 of the body portion, the sets of levers upon the said sides 45 of the sections corresponding in formation arrangement and connection and each set including pivotally interconnected levers 18 and 19, the free extremity of the lever 19 having pivotal bearing as at 20 upon an adjacent portion of its respective side 2 while the free portion of the lever 18 is pivoted as at 21 to the adjacent side of the frame section 8, preferably in proximity to the pivoting of the links 15 to the bearing ears 14. A shorter lever 22 is provided each of the pairs of levers 18 and 19 being pivoted to the same adjacent their point of pivotal interconnection and having the free ends of each pivoted as at 23 50 to the approximate intermediate side portions of the frame section 9, pivotal movement of the levers 22 with respect to the section 9 being limited through the medium of lug like stops 24 formed integral with portions of said 60 opposite sides of the frame section 9 in prox-

imity to the pivotal bearing portions 23 thereupon.

Other sets of toggle levers 25 are provided the opposite sides of the frame section 9, certain of the ends of these levers having pivotal bearing as at 26 upon adjacent portions of the inner sides of the body portion sides 2 while the free extremities of the remaining levers of said pairs are pivoted as at 27 to the normally forward sides of said frame section 9, pivotal movement between the toggle levers 25 being limited by means of stop fingers 28 formed on certain of the same and functioning to limit pivotal movement in the manner illustrated in the Figure 3. Extensions 29 are provided certain of the levers 25 adjacent their pivotal mountings 26 and to these extensions, contractile coiled springs 30 are connected, the opposite extremities of said springs being fixedly connected as at 31 to portions of the sides 2 of the body portion, thus, functioning to normally impart outward swinging movement to those portions of said toggle levers 25 connected thereto.

With a view toward providing the frame section 8 with means for directing or guiding the same into its compartment or chamber 4 in the body portion of the article of furniture, as is shown in the Figure 1, upwardly directed and curved guide ways or tracks 31 are fixed to the inner faces of the opposite sides 2 of the body portion, the lower ends of said guides being open and their upper ends being closed so that guide rollers 32 supported upon certain of the ends of the opposite sides of the frame section 8 will enter the same and thus facilitate movement of the frame to its normal or inoperative position without liability of interference with parts of said body portion in proximity thereto.

To limit outward swinging movement of the various frame sections 7, 8 and 9 through the section 9, stops or abutments 33 are engaged in the lower portions of the body portion sides 2 as is shown in the Figure 4, and with movement of the frame sections to their operative or extended positions, will engage with portions of certain of the toggle levers 25, thereby preventing further outward movement of the sections through the section 9 and 10, insuring arrangement of the bed spring constituting sections in their proper relative positions.

That the extended sections 7 and 8 may be rigidly supported in their operative positions, foldable legs 34 are provided each thereof and suitable mechanism (not shown herein) may be provided for causing said legs to be automatically pivoted to their operative positions simultaneously with extension of the sections carrying them while with return of the frame sections to their inoperative or normal positions, the foldable 120

legs will be caused to pivot to their inoperative positions.

A foldable mattress or pad 35 is provided the frame sections and with extension of the same to their operative positions, said mattress is arranged in an unfolded position thereover. With arrangement of the frame sections in their inoperative positions as is shown in the Figure 1, the mattress is adapted to be folded in the manner shown therein and to be arranged between the relatively superposed sections 7 and 9. Preferably, means are provided the mattress or pad for securing the folds thereof in nested relation, as is shown in the Figure 5, such means being herein illustrated as constituting a metal clip 36 the free end of which is formed with a lip portion 37 adapted to engage in a suitable formed part 38 of one of the portions of the mattress pad while the opposite end thereof is pivoted as at 39 to a portion of the frame 7 or rather, to the mattress 10 thereof. This form of securing means for the mattress pad, however, may be varied, such as conditions or preference may dictate.

In the Figures 6 and 7 I have shown slightly modified form of the invention, the article of furniture 1' herein corresponding to the article of furniture illustrated in the first embodiment but being equipped with only two bed frame constituting sections 7' and 9'. The frame section 7' is connected through links 40 to the opposite side portion and its normally inner extremities of the frame section 9, while toggle levers 25' are provided upon the opposite sides of said frame sections 7' and 9', certain of the ends of said levers being pivotally mounted as at 26' upon adjacent portions of the inner sides of the article of furniture 1' while the remaining ends of said levers are pivoted as at 27' to the normally forward portions of the opposite sides of frame section 9'; an extension 29' being provided upon certain of the toggle levers 25' adjacent their pivotal mountings 26' whereby to permit of the connection of certain of the ends of contractile coiled springs 30' thereto, the remaining ends of said coiled springs being connected as at 31' to appropriate portions of the inner faces of the opposite side of the article of furniture of body portion 1'. Pivotal movement between the several pairs of toggle levers 25 is limited through the medium of stop extensions 28' carried upon certain of the same adjacent their pivotal interconnection.

The section 9', as will be noted upon reference to the Figure 6, is provided with an end or panel board 17' which with arrangement of the frame sections in their normal or inoperative positions will afford an effectual closure for the outer or exposed ends thereof; foldable legs 41 being provided the frame section 7' and adapted, with movement of said section 7' to its extended position to be

brought to operative or supporting positions as are shown in the Figure 7.

A foldable mattress or pad 35' is provided the frame constituting sections 7' and 9' and, as is shown in the Figure 7, with extension or operative positioning of said sections, is adapted to be arranged or extended thereover.

The operation of that form of the invention shown in the Figures 1-5 inclusive may be stated to be as follows: with arrangement of the frame sections 7, 8 and 9 in those positions as is shown in the Figure 1, it will be understood that the article of furniture may be used as a chair or a settee, dependent upon the overall dimensions thereof. When in these normal positions, it will be noted that the panel or closure board 17 will conceal the outer ends of the folded sections 7 and 9 as well as the outer ends of the folded mattress pad 35, while for comfort of the said article of furniture, a removable cushion or pad indicated by the numeral 42 is arranged upon the uppermost frame section 9, that is, the spring section 10 of the same. When it is desired to convert the article into a bed, the uppermost section 9 is pivoted to that position as is shown in the Figure 2, whereupon the toggle levers 25 will be moved to their partially open positions and above center positioning of the pivotal connection between the levers 18 and 19 will be effected in the manner as is also shown in the Figure 2. At this time, the outer end of the section 7 is engaged, as by a hand hold or similar device and is pulled horizontally outwardly. By this pull, the section 7 will be caused to slide outwardly from the body portion 1 of the article of furniture and the section 8 will follow it because of its slideable disposition in the curved tracks or guide ways 31 and its pivotal connection to the links 11 with the section 7. During outward pulling of the sections 7 and 8, the section 8 will move to a substantially horizontal position as is shown in the Figure 3 and during such movement, the levers 18 and 19 will be pivoted to relatively acute angles, thereby imparting an upward thrust to the section 9 through the levers 22 and spreading the toggle levers 25 to the extent of their pivotal movement against the tension of the contractile coiled springs 30 connected to the extensions 29 thereof. This positioning of the parts just described is well illustrated in the Figure 3. The outward pulling of the frame constituting sections is continued and thereby, the levers 18 are swung by the levers 19, such leverage imparting an upward movement to the sections 8 and 9 so that they will be brought to positions as is shown in the Figure 4. With this movement of the sections 8 and 9 to the positions shown in the Figure 4, the toggle levers 25 will be pivoted or swung to those positions as are also shown

in the Figure 4, portions of said toggle levers abutting the stops 33 and hence, limiting the outward pulling of the sections. In this connection, it will be noted that during the 5 extension of the said frame constituting sections to their operative positions, the section 9 will be completely reversed in its position from that shown in the Figure 3 so that when it reaches its ultimate extended or operative 10 position, the panel or cover board 17 thereof will assume that position as shown in the Figure 4 adjacent the upholstered back portion of the article of furniture. It will be thus seen that the levers 18, 19, 22 and 25 will 15 serve as motion transmitting and converting means, that is, effecting the relative reversing and adjustment of the frame constituting sections 7, 8 and 9 with the outward pulling of the section 7 whereby all of said sections 20 may be arranged in their operative or extended positions as is shown in the Figure 4.

When it is desired to return the frame constituting sections, 7, 8 and 9 to their inoperative or normal positions as is shown in the 25 Figure 1, the foldable legs 34 of the sections 7 and 9 are swung inwardly to inoperative positions and the section 7 is thrust or pushed inwardly, thereby lowering the section 8 through the medium of the levers 18 30 and 19 so that the guide rollers 32 thereof will enter the open and lower ends of the curved guideways or tracks 31. With continued inward thrust or pushing of the section 7, the section 8 will be moved upwardly 35 into the chamber 4 of the article of furniture and at the same time, the section 9 will be returned to that position as is shown in the Figure 2, that is, it will be returned to this position when the section 7 is forced or 40 pushed to its folded or inoperative position as is also shown in the Figure 2. At this time, the section 9 may be swung downwardly so as to bring the panel or closure board 17 to that position as is shown in the Figure 45 1, whereupon the article may be used as a chair or a settee, depending as hereinbefore stated, upon the overall dimensions of the device. The removable pad or cushion 42 may be then arranged upon the uppermost 50 section 9.

In operation of the form of the invention disclosed in the Figures 6 and 7, the sections 7' and 9' are normally arranged in those positions as is shown in the Figure 6, where- 55 upon the device may be used as a settee, depending upon the dimensions thereof. To convert the article into a bed, the section 7' is engaged to a hand hold or similar appliance and is pulled outwardly, subsequently 60 to the raising of the section 9' to a position whereat the cover board or panel 17' will be removed from the outer end of said section 7'. This outward pulling of the section 7' will cause the section 9' to follow it and 65 during such following movement, said sec-

tion 9' will be completely reversed in its position from that as shown in the Figure 6 so that the panel or closure board 17' will be brought to that position as is shown in the Figure 7, this reversal or positioning of the section 9' being effected through the movement between the toggle levers 25' and the pivotal connection of the links 40 between the sections 7' and 9'. When in operative or extended positions, it will be noted that the foldable supporting legs 43 of the section 7' are brought to operative or supporting positions, thus supporting the same in the manner as illustrated in the Figure 7. To return the bed frame constituting sections 7' and 9' to their inoperative or normal positions, it is only necessary that the legs 43 be returned to their folded or inoperative position and that an inward thrust be imparted to the section 7', this causing a lowering of the now forward end of the section 9' and a pivotal reversing of its position together with the sliding of the section 7' to that position as is shown in the Figure 6. At this time, the diagonally or inclined upper section 9' is pivoted downwardly so as to bring the cover or panel board 17 to its position over the now outer ends of the frame constituting sections 7' and 9' together with the outer ends or extremities of the folded mattress or pad 35.

Manifestly, the construction shown is capable of considerable modification and such modification as is within the scope of my claims, I consider within the spirit of my invention.

I claim:

1. Convertible furniture comprising a chair like body portion, a plurality of bed frame constituting sections, links pivotally interconnecting said bed frame sections and permitting of relative swinging and pivotal movement therebetween, the back of said body portion having a fixed chamber formed therein adapted to receive, at times, one of said frame sections therein in substantially vertical position and the lower portion of said body portion being adapted to receive the remaining frame sections therein in superposed relation, guide means upon the opposite sides of said body portion for directing one of said frame sections into said chamber, pivotally interconnected motion transmitting and converting levers adjacent the opposite sides of the body portion having certain of their ends pivoted to portions of certain of said frame sections and their remaining ends pivoted to the inner sides of said body portion, toggle levers mounted adjacent the opposite sides of said body portion having certain of their ends pivoted thereto and the remaining ends thereof pivoted to one of said frame sections, and mattress sections carried by each of said frame sections.

2. A chair bed comprising a chair frame

130

- and a plurality of bed sections mounted therein, two of the sections being housed one above the other, and a third section extending vertically and substantially above the other
- 5 two and at the rear thereof, and link connections between the several sections and the chair frame for extending the bed sections in horizontal alinement when unfolded with the aforementioned rear section interposed
- 10 between the other two sections.
3. In a convertible seat bed, a fixed back extending downwardly from the top of the frame, providing a space between it and the back of the frame, a plurality of connected bed sections foldable in the chair frame, means for overturning one of the sections in the frame, means for guiding another of the sections into the said space, and connections between this last section and two other sections whereby the last section is extended in alignment between the other sections when they are unfolded.
4. A convertible seat bed having a frame with a fixed back extending forwardly to provide a space between it and the back of the frame, a sectional folding bed having connected sections, means for mounting one section to move upwardly into said space, another section forming a seat and another
- 25 section disposed below the seat, and connections between the sections and between certain of the sections and the frame for positioning the back section in alignment between the other two when they are unfolded
- 30 to form a bed.
5. In a convertible seat bed, a frame having a fixed lower back support providing an unobstructed space behind it at the rear of the frame, a folding bed comprising a number of separate sections, one normally disposed in a vertical position at the back of the frame, another forming the seat, and a third at the bottom of the frame below the seat, means forming separate connections between the rear section and each of the other two sections and between certain of the sections and the frame whereby the sections will be moved into alignment with the rear section between the other two in unfolding them
- 45 to form a bed, and means for mounting the seat section for inversion within the frame when the sections are moved into alignment.
6. A convertible bed having a frame with a fixed back support at a distance below the top and from the back of the frame to provide an unobstructed vertical space at the rear of the frame, a plurality of bed sections foldable in the frame, one section extending vertically into said space, a seat section extending below the lower back support, and another section at the bottom of the frame below the seat section, means forming connections between the sections and between certain of the sections and the frame,
- 55 that of the seat section extending upwardly
- in the folded position of the sections above and behind the lower edge of said back support, and means for withdrawing the lower and back sections and inverting the seat section in placing the sections in alignment to form a bed.
7. In a convertible seat bed, a fixed back forming a space at the rear of the frame, a back section movable upwardly into vertical position in the space, a seat section having a connection with the back section from a point below the back to a point above the lower edge thereof, permitting an upward swinging movement of the seat section about the rear thereof, another section below the seat having a connection with the lower end of the rear section, means forming a connection between certain of the sections and the frame for supporting them therein and for invertibly mounting the seat section within the frame whereby the seat section is inverted by the movement of the other sections into alignment when the seat section is tipped upwardly at the front to uncover the section below the seat.
8. A convertible seat bed having a seat section with an attached front board, a rear section disposed in a vertical position at the rear of the frame, another section mounted below the seat section and connected to the lower end of the rear section and covered by the front board, means for connecting the rear end of the seat section to the upper portion of the rear section at a distance from its upper end, means forming a supporting and
- 90 cooperating relation between the sections and the frame and for mounting the seat section in the frame for invertible movement, the connection between the seat section and the rear section permitting the front board to be raised with the seat section to uncover the front end of the lower section whereby the sections may be pulled outwardly into alignment with the rear section between the other two and the seat section inverted within the frame.
9. In a convertible seat bed, a plurality of sections connected for folding movement into and out of the seat frame, one of the sections being disposed at the rear of the frame, another section forming the seat, and another section being disposed at the bottom of the frame below the seat, means for connecting the sections for extension into alignment with the rear section disposed between the other two sections, and means forming a supporting and
- 95 cooperating relation between certain of the sections and the frame and for invertibly mounting the seat section in the frame, said means comprising a plurality of connected pairs of levers at each side of the seat section, one lever of each pair being connected to the seat section and the other lever of each pair being connected to the seat frame, the pairs of levers permitting the seat section
